UNITED STATES PATENT OFFICE.

PAUL ACHILLE JOSEPH COUSIN, OF LOOS-LEZ-LILLE, NORD, FRANCE.

GAS-FURNACE.

1,072,578.

Specification of Letters Patent.

Patented Sept. 9, 1913.

Application filed January 7, 1913. Serial No. 740,669.

To all whom it may concern:

Be it known that I, PAUL ACHILLE JOSEPH COUSIN, citizen of the Republic of France, residing at 84 Rue Faidherbe, Loos-5 lez-Lille, Nord, in the Republic of France, have invented new and useful Improvements in Gas-Furnaces, of which the following is a specification.

My invention relates to improvements in 10 gas furnaces used for melting metals or other purposes.

One object of my invention is to provide a reducing burner formed of two vertical flues, one for the gas, located near the furnace 15 chamber and the other for air, which are separated by a wall terminating on a level much below the point where the flues run into the furnace chamber, so that a combustion and expansion chamber is thus 20 formed for the flame, which chamber is located below the point of introduction of the flame into the heating chamber of the furnace. By this arrangement, I am able to obtain the exact length of flame desired, 25 to bring the part of said flame where the temperature is at its maximum to the part of the furnace chamber most convenient according to the requirements and to insure that an excess of gas shall come into contact 30 with the material to be treated, which aids in the reducing effect.

Another object of my invention is to combine in a furnace a reducing burner of that kind, arranged at one end of the furnace 35 chamber with oxidizing burners arranged at both sides of said chamber. By this arrangement, the flames of the oxidizing burners are directed in the furnace chamber in a direction at right angles to the reducing 40 flame, whereby the two fluids, gas and air, of said flame are thoroughly mixed and the combustion thereof is improved. Moreover, it is thus possible to effect in the same furnace either operations which require an oxidizing atmosphere at certain times and a 45 reducing or neutral atmosphere at other times, or operations which only require an oxidizing, reducing or neutral atmosphere, respectively, and to obtain in all cases the 50 temperature desired with the best conditions for a perfect combustion.

In the annexed drawings: Figure 1 is a longitudinal section along the line 1—1, Fig. 55 2 of a furnace with lateral oxidizing burners and a reducing burner located at one end of the furnace. Fig. 2 is a horizontal

sectional view substantially on the line 2—2, of Fig. 1; Fig. 3 is a similar view substantially on the line 3—3 of Fig. 1; Fig. 4 is a vertical sectional view substantially on the line 4—4 of Fig. 1; Fig. 5 is a similar view substantially on the line 5—5 of Fig. 1; Fig. 6 is a similar view substantially on the line 6—6 of Fig. 1; Fig. 7 is a similar view substantially on the line 7—7 of Fig. 1; Fig. 8 is a similar view substantially on the line 8—8 of Fig. 1; Fig. 9 is a similar view substantially on the line 9—9 of Fig. 1; Fig. 10 is a similar view substantially on the line 10—10 of Figs. 2, 3, 5 and 9; Fig. 11 is a vertical sectional view, substantially on the line 11—11 of Fig. 12 of a modified form of invention embodying a rotary furnace having a cylindrical furnace chamber; Fig. 12 is a similar view substantially on the line 12—12 of Figs. 11 and 13; Fig. 13 is a horizontal sectional view substantially on the line 13—13 of Fig. 12.

The furnace shown in Figs. 1 to 13 has a heating chamber *a* in which the material 80 to be treated is placed either in bulk or in crucibles, retorts, etc. Said chamber *a* is provided with a door *b*, a bed *m*, a tapping hole *n* and two lateral smoke flues *o* (Figs. 1, 3, 8). A block *A*, preferably provided 85 in the back wall of the furnace may be removed for repairs. Man holes *B* permit of inspecting the working of the furnace.

The furnace is provided with a reducing burner *b* arranged at the rear end of the 90 furnace chamber *a* and provided with a chamber *q* into which gas and air are led respectively by parallel vertical flues *r* *s* (Fig. 2) separated from each other by a vertical transverse wall *t*, the gas flue *r* being nearer the furnace chamber *a*. The burner chamber *q* forms with the furnace chamber *a* a continuous chamber having in its wall no projecting or abrupt parts adapted to form eddies, so that from the ends of 100 the vertical flues *r* *s*, to the smoke exhaust flues *o* both currents of fluid, air and gas, remain parallel, the combustion being effected gradually along the way of the gases. As the gas is led under the air, an excess of gas 105 is kept in contact with the material treated, whereby the reducing effect is aided. The gas is led to the flue *r* by a horizontal flue *f* (Fig. 2) from a flue *d* through a regulating valve *C*. The air is led to the flue *s* by a 110 similar flue *g* from a flue *e* through a regulating valve *D*. Each of the flues *r* *s* is

divided into two conduits by vertical longitudinal partition: u in the gas flue r and v in the air flue s Figs. 9 and 5, and the horizontal flues f, g are similarly divided by projecting partitions w, x which merge, respectively, into the partitions u and v . The partitions u, v, w, x , act to equalize the draft so that a uniform flame is obtained in the whole cross section of the furnace chamber a .

10 The number of partitions may be augmented if desired.

It will be seen that the wall t between the gas and air flues terminates on a level much below that on which the flame is introduced into the furnace chamber a , so that a mixing chamber q is formed in which the flames can expand. A damper E (Fig. 1) is provided preferably in the back wall of the furnace for regulating the action of the reducing burner.

15 The furnace is also provided with oxidizing burners arranged at both sides of the chamber a and shown as being five in number on each side. Each of said burners comprises a horizontal flue c which opens into the chamber a and is fed with gas and air by means of two vertical parallel flues F, G (Fig. 5) respectively, said flues being in the same transverse plane of the furnace.

20 The current of air is thus deflected at right angles in its passage from the flue G to the flue c so that the two currents of air and gas flow in perpendicular directions at the point where they meet, where ignition occurs. An excess of air is necessary for obtaining an oxidizing action. The flames thus obtained are short and very hot; they are directed transversely through the furnace chamber a . If the burners c are placed

25 sufficiently near to each other, the flames thereof meet each other in the direction of the length of the furnace and are mixed and stirred together which aids in obtaining a rapid and complete combustion. Dampers H (Fig. 5) permit of regulating each of the oxidizing burners separately.

30 The gas flues F (Fig. 10) are in communication at the bottom with horizontal flues F^1 connected by vertical flues F^2 with lower longitudinal horizontal flues j to which air is fed from the flues d through valves h . The air flues G are in communication by flues G^1 similar to F^1 and vertical flues G^2 similar to F^2 with longitudinal horizontal flues i to which air is fed from the flue e through valves k .

35 The gas may be taken directly from the gas producer or other convenient source or heated in a regenerator; it is led by a flue d^1 (Figs. 1, 2) to the transverse flue d carrying the valve C and both valves h . The heated air coming from the regenerator is led to the valve carrying flue e by a similar flue e^1 (Figs. 1, 2). The regenerators may be

40 arranged under the furnace and serve as a

foundation for the same. The smoke escapes through the lateral openings o (Fig. 4) and the two vertical flues p which communicate by means of transverse horizontal flues K with a longitudinal horizontal flue L (Fig. 2) where the smoke is collected and led into a flue M leading to the stack not shown. At the point where both flues K run into the longitudinal flue L , the latter is provided with a vertical longitudinal partition N by which direct communication between the flues K is prevented and the draft made more uniform on both sides of the furnace whatever the location of the stack may be. Two dampers P (Fig. 4) are provided in the vertical flues p on both sides of the furnace. It is thus possible to reduce at will the section of passage of the smoke through said flues and to entirely cut off the furnace from the stack when the furnace is stopped, as shown in Fig. 4.

45 When the furnace is used for melting metals and is not worked continuously, the combination of the reducing and oxidizing burners has special advantages as the beginning of an operation is difficult because the furnace chamber is given opportunity to cool between operations; the oxidizing burners, either alone or in combination with the reducing burner permit the furnace to be 50 then heated rapidly while the reducing burner is only kept working in normal conditions and particularly at the end of the melting operation when any oxidation which would be detrimental to the quality 55 of the metal obtained must be avoided. When the furnace is operated without interruption, the oxidizing burners may be omitted.

50 Referring to the modified form of invention illustrated in Figs. 11 to 13, a^{10} designates the cylindrical furnace chamber to which the air and gas pass from the chamber q^{10} , said chamber being provided with the tapping opening n^{10} . The air and gas 55 pass to the chamber q^{10} from the flues s^{10} and r^{10} respectively, which communicate with the horizontal flues g^{10} and f^{10} respectively. A^{10} is a block or plate removably inserted in the back wall of the furnace to 60 permit access to the interior, for purposes of repair and the like, and B^{10} designates a suitable manhole formed in the back wall of the furnace. E^{10} designates a damper adjacent the reducing burner for regulating 65 the action thereof; P^{10} designates an additional damper in vertical flues p^{10} leading to the smoke escape flues o^{10} , and K^{10} designates a transverse horizontal smoke escape flue in the base of the furnace. The operation of the modified form of the invention is substantially the same as that of the preferred form and requires no additional description.

Having now described my invention, what 70

I claim as new and desire to secure by Letters Patent is:

1. In a furnace, in combination, a heating chamber, two parallel vertical flues, 5 means for leading a combustible gas to the vertical flue adjacent the heating chamber, means for leading air to the other vertical flue, a vertical wall separating the flues from each other, said wall terminating on 10 a level substantially lower than the bottom of the heating chamber so as to form a vertical expansion chamber into which the said flues open at one end and in communication at its upper end with the heating chamber, 15 substantially as described and for the purpose set forth.

2. In a furnace in combination: a heating chamber, parallel vertical flues in communication with one end of the heating chamber, 20 means for leading a combustible gas to one of said flues, means for leading air to another of said flues, vertical flues arranged at the sides of the heating chamber, said flues being arranged in pairs in trans- 25 verse planes, a horizontal flue connecting both flues in each pair at the upper end and opening into the heating chamber and means for supplying air to one of the flues in each pair and a combustible gas to the other flue, 30 substantially as described and for the purpose set forth.

3. In a furnace, in combination: a heating chamber, parallel vertical flues located at one end of the heating chamber, means 35 for leading a combustible gas to one of said flues, means for leading air to another of said flues, an expansion chamber into which the said flues open at one end and in communication at the other end with the heating chamber, vertical flues arranged at the 40 sides of the heating chamber, said flues being arranged in pairs in transverse planes,

a horizontal flue connecting both flues in each pair at the upper end and opening into the heating chamber and means for supplying air to one of the flues in each pair and a combustible gas to the other flue, substantially as described and for the purpose set forth. 45

4. In a furnace in combination: a heating 50 chamber, two parallel vertical flues located at one end of the heating chamber one of said flues being immediately adjacent said chamber, means for leading a combustible gas to the vertical flue adjacent the heating 55 chamber, means for leading air to the other vertical flue, an expansion chamber into which the said flues open at one end and in communication at the other end with the heating chamber, vertical flues arranged at 60 the sides of the heating chamber, said flues being arranged in pairs in transverse planes, a horizontal flue connecting both flues, in each pair at the upper end and opening 65 into the heating chamber, means for supplying air to one of the flues in each pair and a combustible gas to the other flue, smoke openings in the side walls of the heating chamber at the end remote from the first named vertical flues, side flues connected to 70 said openings, a longitudinal exhaust flue connected to said side flues and a vertical longitudinal partition in said longitudinal flue at the point of junction with the side flues, substantially as described and for the 75 purpose set forth.

In testimony whereof I have signed my name to this specification in the presence of two subscribing witnesses.

PAUL ACHILLE JOSEPH COUSIN.
